What is the best beach wagon for sand, article published on Aug. 13, 2021, site visited Dec. 20, 2023, <https://hunterarchdall.blogspot.com/2021/08/what-is-best-beach-wagon-for-sand.html> (Year: 2021).*

Primary Examiner — Cynthia Ramirez

(74) *Attorney, Agent, or Firm* — Jose Cherson Weissbrot

(57)

CLAIM

The ornamental design for a beach wagon, as shown and described.

DESCRIPTION

FIG. 1 is a perspective view of a beach wagon showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

Broken lines in the drawings depict portions of the beach wagon that form no part of the claimed design.
